SHEET SEPARATING APPARATUS

William Richard Schmitz, Jr., Buffalo, N. Y., assignor to E. I. du Pont de Nemours & Company, Wilmington, Del., a corporation of Delaware

Application June 1, 1940, Serial No. 338,441

9 Claims. (Cl. 271—43)

The present invention relates to an apparatus for continuously and automatically feeding, in an intermittent manner, a successive series of sheets of fibrous cellulose material to a receiving device. The apparatus of the present invention has particular utility in the automatic, continuous feeding of relatively stiff, coarse sheets of wood pulp or cotton linters.

It is an object of the present invention to provide an apparatus for the continuous and automatic feeding of sheets of fibrous cellulose from a stack of such sheets closely packed in an upstanding position on a moving conveyor.

It is a further object of this invention to slowly move, as a unit, a large number of closely packed upstanding sheets of fibrous cellulose toward a receiving member and to periodically separate one or more of these sheets from the unit and pass the same into a receiving device.

Other objects of the invention will appear hereinafter.

The apparatus of the present invention, in its broad aspects, comprises, in combination, a moving conveying apparatus upon which a stack of sheets of fibrous cellulose are placed in an upstanding position, and a sheet separating and feeding mechanism which is so constructed and arranged, relative to the conveying apparatus, as to move between the sheets of the stack to separate one or more of the sheets from the forward end of the stack and move the separated sheet or sheets from the conveyor to a receiving device.

The details of the apparatus will be more clearly apparent by reference to the following description when taken in connection with the accompanying illustrations, in which:

Fig. 1 is a sectional view, with parts shown in elevation, taken along the line 1—1 of Fig. 2.

Fig. 2 is a front elevational view of a sheet feeding apparatus constructed in accordance with the present invention.

Fig. 3 is a side elevational view, on a slightly smaller scale, of the apparatus shown in Fig. 2.

Fig. 4 is a top plan view of a sheet supporting member.

Fig. 5 is a side elevational view of the sheet supporting member of Fig. 4.

Fig. 6 is a front elevational view of a slightly modified form of sheet feeding apparatus constructed in accordance with the present invention.

Referring to the illustrations, reference numeral 11 designates a stack of closely packed sheets of pulp wood, or the like, positioned in an upstanding manner on a pair of spaced parallel

conveying belts 13. The conveying belts 13 are moved by means of a plurality of pulleys 15 mounted on a common shaft 16. The shaft 16 is rotated in a step-wise manner by means of a conventional pawl and ratchet mechanism comprising a stationary spring pressed pawl 19, an oscillating pawl 21, and a rotatable ratchet wheel 17. The oscillating pawl is actuated by connection with an oscillating lever 23 which is rotatably mounted on shaft 16 and is oscillated by the rotating cam 25. The lever 23 is provided with a follower wheel 21 and a coiled compression spring 31 which is adapted to maintain the follower wheel 21 in contact with cam 25. The spring 31 is connected between the two pawls 19 and 21 and, therefore, also functions to maintain both pawls in contact with ratchet wheel 17.

The sheet separating and feeding mechanism comprises a reciprocating bar 33 which is adapted to move in a fixed support 35 and is maintained in contact with eccentric cam 29 by means of the coiled compression spring 37. Cams 25 and 29 are both fixed mounted on rotating shaft 26. The reciprocating bar 33 is provided with a sheet separating blade 39. The blade 39 is preferably positioned below the stack of sheets 11 and between the two conveying belts 13. The blade 39 is pivoted to the reciprocating bar 33, and is provided at opposite sides thereof with projecting riders 41. The riders 41 are positioned in slots or grooves in supporting member 43. The slot or groove of the supporting member 43 is curved adjacent the extreme outward end thereof, as shown by reference 45. It is, therefore, evident that upon reciprocating the bar 33 towards the stack of sheets, the blade will move upwardly between two of the sheets and as the blade continues to move upwardly it will be oscillated in a right-hand direction, as shown in the drawings, as a result of the riders 41 following in the groove 45. The blade 39 is positioned in overlapping relationship to a sheet holding member 47. The top of the sheet holding member 47 is provided with an arcuate sheet guiding member 49. In operation the apparatus functions substantially as follows:

Upon rotation of the cam 25, the pawl and ratchet mechanism is moved to advance pulley 15 and thereby advance the stack of sheets 11. Cam 29 then reciprocates bar 33 upwardly causing the blade 39 to be inserted between two sheets of the stack 11. As the blade 39 approaches the end of its upward movement it is caused to oscillate due to the path of the riders 41 in the angular groove 45, and thereby separates one or

more of the sheets from the forward end of the stack 11 and moves the same from the stack. The sheet holding member 47 remains in contact with the sheets at the forward end of the stack. The bottom of the sheet is contacted by the arcuate sheet guiding member 49 and the blade 39 is adapted to slide the sheet outwardly on guiding member 49. The sheets moving from the stack 11 are flipped into a hopper 15, or the like, which is adapted to convey them to any desired receiving means (not shown).

Referring to Figs. 3, 4, and 5 of the drawings, the stack of sheets may be positioned on the conveying belts 13 by means of a sheet supporting member 51. The sheet supporting member 51, filled with sheets, may be positioned against the back of the preceding sheet supporting member. The preceding sheet supporting member 51 may then be removed from the stack by merely pulling it sidewise from the stack of sheets resting on the sheet conveying belts 13. In this manner one sheet supporting member will support all of the sheets on the conveyor in an upstanding position. The sheet supporting members are comprised of a substantially flat bottom member 53 and a substantially flat back member 55, the two members being rigidly connected to each other and strengthened by means of a brace 51. The bottom member 53 must, of course, be sufficiently long that when the sheet supporting device is filled it will remain in an upright position on the conveyor. The brace 51, or, if desired, several of such braces, must be positioned only on one side of the members 53 and 55 so that the sheet supporting member can be slid from the stack in a sidewise direction. A handle of any desired form may be connected to the brace 51.

Referring to Fig. 6 of the drawings, the stack of sheets 11 is moved on a single conveying belt 13a driven by pulley 15a. The sheet separating and feeding mechanism is positioned adjacent the forward end of the stack of sheets beside the pulley 15a. The sheet separating and feeding apparatus is comprised of substantially the same mechanism above-described, and the blade of this mechanism is adapted to be inserted between sheets at one side of the stack. This form of apparatus is less desirable, nevertheless, is operative to feed successive sheets into a receiving means in the same manner as in the apparatus above-described. In moving the sheets from the stack in this modified form of apparatus, the sheet will be moved from its lower-left-hand corner as shown in Fig. 6, and it will, therefore, be twisted sidewise slightly during the feeding thereof. By utilizing a hopper of large area, this twisting of the sheet will be unobjectionable.

Although the above-described forms of apparatus are the preferred embodiments of the invention, it is obvious that many changes and modifications can be made in the detailed construction thereof.

It is not necessary that the pulleys 15 and the conveying belts 13 be driven in a stepwise manner. These members may be driven in a continuous manner, at a relatively constant speed, so that the sheet separating and feeding mechanism, operated at a constant speed of reciprocation will permit the feeding of a predetermined number of sheets at each reciprocation of the sheet feeding member. Obviously, the reciprocating bar 33 may be given a reciprocating motion by other means than a cam. Furthermore, the reciprocating and oscillating motion of the sheet separating blade 39 may be given the re-

ciprocating and oscillating motion by numerous different forms of apparatus. The blade 39 need not necessarily have an oscillating motion, it being only necessary that the blade, after being inserted between sheets, move away from the forward end of the stack.

In the drawings, the reciprocating bar 33 and the blade 39 are shown mounted at an angle, corresponding to the angle at which the sheets are positioned upon the conveying belts. Although this is desirable, it is not an essential feature of the present invention, and the mounting of the reciprocating bar and the sheet separating blade may be at a different angle than that of the sheets in the stack. The number of sheets fed from the stack at any reciprocation can be determined by the ratio of the speed of reciprocation of the sheet separating and feeding mechanism and the speed of the conveying belts 13.

The preferred embodiment of the invention contemplates the mounting of the sheet separating and feeding device below and between the two spaced parallel conveying belts, or at one side of a single conveying belt for the sheets, as illustrated in Fig. 6. The sheet separating device may, however, be located above the stack of sheets with the blade of the device acting in a downward direction to affect the separation of the sheets from the stack, or the device may be positioned at one side of the stack of sheets to separate and move the sheets away from the stack with an efficiency, substantially equivalent to the device above-described.

The present invention provides a very satisfactory sheet feeding device for the continuous, automatic feeding of sheets of fibrous cellulose, such as wood pulp or cotton linter sheets, in the preparation of alkali cellulose solutions.

The device of the present invention has particular utility where it is desired to feed sheets at a slow rate to a receiving means for a continued period of time. The conveying belts 13 may be made of any desired length, and thereby any number of cellulose sheets may be positioned in the stack on the sheet conveying apparatus. The apparatus of the present invention will operate for extended periods of time in an automatic manner and without trouble from clogging, or jamming. The relative speeds of the conveying belt and the sheet separating and feeding mechanism may be readily adjusted to any speed ratio to give any desired rate of feeding of the sheets.

Since it is obvious that many changes and modifications can be made in the details above-described, it is to be understood that the invention is not to be limited to the specifically described details, except as set forth in the appended claims.

I claim:

1. A sheet separating apparatus, adapted to remove sheets from a stack of sheets on an advancing conveyor, which comprises blade means for intermittently separating and forcing one or more sheets from said stack, means for inserting said blade means between sheets of said stack, hinge means connecting said blade means to said inserting means, and means for moving said blade on said hinge means in a direction away from said stack.

2. A sheet separating apparatus, adapted to remove sheets from a stack of sheets on an advancing conveyor, which comprises blade means for intermittently separating and forcing one or more sheets from said stack, means for recipro-

cating said blade means whereby to cause the same to be periodically inserted between sheets of said stack, and means for oscillating said blade means whereby to move the same in a direction away from said stack.

3. A sheet separating apparatus, adapted to remove sheets from a stack of sheets maintained in an upstanding position on an advancing conveyor, which comprises blade means below said stack for intermittently separating and forcing one or more sheets from said stack, means for inserting said blade means between sheets of said stack, hinge means connecting said blade means to said inserting means, and means for moving said blade on said hinge means in a direction away from said stack.

4. A sheet separating apparatus, adapted to remove sheets from a stack of sheets on an advancing conveyor, which comprises blade means positioned below the forward end of the advancing stack of sheets, means for intermittently inserting said blade means between sheets of said stack, hinge means connecting said blade means to said inserting means, and means for moving said blade on said hinge means, after the insertion thereof, in a direction away from said stack.

5. A sheet separating apparatus, adapted to remove sheets from a stack of sheets on an intermittently advancing conveyor, which comprises blade means for intermittently separating and forcing one or more sheets from said stack, means for inserting said blade means between sheets of said stack, hinge means connecting said blade means to said inserting means, and means for moving said blade on said hinge means in a direction away from said stack, said conveyor moving means and said sheet separating means being synchronously driven at a predetermined speed ratio.

6. A sheet separating apparatus, adapted to remove sheets from a stack of sheets on an advancing conveyor which comprises blade means

adjacent the forward end of the advancing stack of sheets, means, synchronized to the speed of said conveyor advancing means, for reciprocating said blade means whereby to intermittently insert the latter between sheets of said stack, and means for imparting an oscillating motion to said blade means whereby to move the same, together with one or more sheets, in a direction away from said stack.

10 5 15 20 25 30 35 40

7. A sheet separating apparatus, adapted to remove sheets from a stack of sheets on an advancing conveyor which comprises blade means adjacent the forward end of the advancing stack of sheets, means synchronized to the speed of said conveyor advancing means, for reciprocating said blade means whereby to intermittently insert the latter between sheets of said stack, and means for imparting an oscillating motion to said blade means whereby to move the same, together with one or more sheets, in a direction away from said stack, and means adjacent said blade means for supporting and guiding the sheets which are separated and moved from said stack.

8. A sheet separating apparatus, adapted to remove sheets from a stack of sheets on a pair of advancing spaced parallel conveyors, which comprises blade means between said conveyors adjacent the forward end of the advancing stack of sheets, means, synchronized to the speed of said conveyor advancing means, for reciprocating said blade means whereby to intermittently insert the latter between sheets of said stack, and means for imparting an oscillating motion to said blade means whereby to move the same, together with one or more sheets, in a direction away from said stack.

9. A sheet separating apparatus as defined in claim 8 in which means are provided for supporting the forward end of said advancing stack of sheets during the oscillating motion of said blade means.

WILLIAM R. SCHMITZ, JR.
